UNITED STATES PATENT OFFICE.

ROBERT BARNES AND ORLEY M. DRAKE, OF DAVENPORT, IOWA.

LOSS-PREVENTING DEVICE.

1,171,381.

Specification of Letters Patent.

Patented Feb. 8, 1916.

Application filed May 12, 1915. Serial No. 27,682.

To all whom it may concern:

Be it known that we, ROBERT BARNES and ORLEY M. DRAKE, citizens of the United States, residing at Davenport, in the county 5 of Scott, State of Iowa, have invented a new and useful Loss-Preventing Device, of which the following is a specification.

The structure forming the subject matter of this application is a loss preventing device, adapted to be assembled with a note book, a spectacle case or the like, for the purpose of holding such articles engaged with a garment pocket.

One object of the invention is to provide 15 a structure of the sort above mentioned which will adequately reinforce the note book or other article against the pressure of a spring tongue whereby the device is held assembled with the garment pocket.

20 Another object of the invention is to provide a structure of the sort above mentioned which is so counterweighted that it will at all times assume a vertical position, thereby to engage readily and securely with the edge 25 of a garment pocket.

It is within the province of the disclosure to improve generally and to enhance the utility of devices of that type to which the present invention appertains.

30 With the above and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

40 In the accompanying drawing:—Figure 1 shows in elevation, a portion of the outer face of one cover of a note book, the loss preventing device forming the subject matter of this application being assembled with 45 the book cover; Fig. 2 is an elevation showing the opposite face of the cover of the book from that delineated in Fig. 1, the book being in an open position, and one cover of the book being broken away; Fig. 3 50 is a section taken approximately on the line 3—3 of Fig. 1 parts appearing in elevation; Fig. 4 is a view similar to Fig. 1, the book, however, having been turned into a horizontal position.

55 Although the loss preventing device forming the subject matter of this application is

adapted to be assembled with articles of different sorts, it has been presupposed that the article to be retained is a note book comprising a cover 1 and a cover 2, the hinge union between the covers being indicated at 3.

The numeral 4 indicates the inner face of the cover 1 and the numeral 5 designates the outer face of the cover 1.

In carrying out the present invention there is provided a spring tongue 6 comprising an arch 7, a reduced neck 12 and a connection in the form of a stud 9 disposed approximately at right angles to the tongue. 70 The stud 9 is threaded as shown at 10, and the free end of the tongue 6 is flexed outwardly to form a guiding finger 8.

The invention comprises a backing strip 11 with which the threaded stud 9 is engaged. The tongue 6 and the backing strip 11 preferably are fashioned from metal. The strip 11 and the tongue 6 are of approximately the same length and the elements in question are held in alinement. 75

In practical operation, an opening 14 is fashioned in the cover 1, the stud 9 is inserted through the opening, and the strip 11 is threaded onto the stud, the strip and the tongue 6 lying in alinement. The strip 11 coacts with the rear or inner face 4 of the cover 1, and the tongue 6 co-operates with the outer face 5 of the cover 1. The stud 9 is of circular cross section so that it may 80 rock in the opening 14 in the cover 1.

In practical operation, as will be understood readily, the book of which the cover 1 constitutes a part is thrust into a garment pocket, the spring tongue 6 bearing against the outer face of the garment pocket, to hold the book in firmly against displacement. The strip 11, being alined with the tongue 6, reinforces the cover 1 of the book against the pressure of the spring tongue 6. 95

It has been pointed out hereinbefore that the stud 9 is mounted to rock in the opening 14 of the cover 1. Therefore, no matter how the book is inserted into the garment pocket, the tongue 6 always stands vertically, so that it will engage properly with the upper edge of the garment pocket. In this connection it is to be observed that the strip 11 which is alined with the tongue 6 and swings therewith, acts as a counterweight securing the vertical positioning of the tongue 6. This operation will be understood clearly from Fig. 4 of the drawings, 100 105 110

wherein the book is shown as positioned horizontally, as might be the case if the book were to be inserted into the lower, watch pocket of a vest, as distinguished from the upper, pencil carrying pocket of the vest.

From the foregoing it will be observed that no matter what the position of the book with respect to the vertical may be, the tongue 6 always hangs vertically and is in a position to engage with the upper edge of the garment pocket.

Having thus described the invention, what is claimed is:—

- 15 1. A loss preventing device comprising a spring tongue, a backing strip substantially co-extensive in length with the tongue, and an article piercing connection uniting one end of the tongue with the corresponding end of the strip, the strip being alined with the tongue thereby to reinforce against the action of the tongue, the article wherewith the device is assembled.
- 20 2. A loss preventing device comprising a

spring tongue, a backing strip alined with the tongue, and an article piercing connection uniting the tongue with the strip, the connection being of circular cross section to permit the same to be article-journalized, whereby the backing strip will act as a counterweight for the tongue and hold the latter in a vertical, depending position.

3. The combination with a pocket-carried article, of a pocket-engaging tongue journaled in the article; and a counterweight 35 distinct from the tongue and assembled with the tongue, the counterweight constituting a means for holding the tongue vertical, irrespective of the position of the article with respect to the vertical.

In testimony that we claim the foregoing as our own, we have hereto affixed our signatures in the presence of two witnesses.

ROBERT BARNES.
ORLEY M. DRAKE.
